CLAIM

The ornamental design for a combined watch and bracelet, as shown and described.

DESCRIPTION

FIG. 1 is a front elevation of a combined watch and bracelet showing our new design;

FIG. 2 is a rear elevation thereof;

FIG. 3 is a side view of the right side of the watch and bracelet

FIG. 4 is a side view of the left side of the watch and bracelet

FIG. 5 is a perspective view of the watch and bracelet; and,

FIG. 6 is an end view of the watch and bracelet.

The broken lines in the drawings are used to illustrate portions of the watch that do not form part of the claimed design. The watch bracelet is shown in an assembled position in FIGS. 3, 4, 5 and 6.
